DECANTER

Hyman C. Berkowitz, Wendell, Idaho, assignor to Berke Brothers Distilleries Inc., Boston, Mass.,
a corporation of Delaware

Application March 30, 1953, Serial No. 24,241

Term of patent 14 years

(Cl. D58—8)

To all whom it may concern:

Be it known that I, Hyman C. Berkowitz, a citizen of the United States, residing at Wendell, in the county of Gooding and State of Idaho, have invented a new, original, and ornamental Design for a Decanter, of which the following is a specification, reference being had to the accompanying drawings, forming a part thereof.

In the drawings:

Fig. 1 is a top view of a decanter, showing my new design;

Fig. 2 is a front elevation of the decanter; and

Fig. 3 is a side elevation looking to the left of Fig. 2.

The elevation looking to the right of Fig. 2 is substantially as shown in Fig. 3.

The sides not shown are the same as those shown.

I claim:

The ornamental design for a decanter, substantially as shown and described.

HYMAN C. BERKOWITZ.
